Oly Williams

UNITED STATES PATENT OFFICE.

OLLY WILLIAMS, OF ST. LOUIS COUNTY, MISSOURI.

METHOD OF ALLOWING FOR EXPANSION AND CONTRACTION OF WIRE FENCES.

Specification of Letters Patent No. 21,459, dated September 7, 1858.

To all whom it may concern:

Be it known that I, OLLY WILLIAMS, of the county of St. Louis, in the State of Missouri, have invented a new and Improved 5 Mode of Constructing, Making, and Erecting Wire Fences; and I do hereby declare that the following is a full, clear, and exact description thereof, reference being had to the accompanying drawings and the letters 10 of reference marked thereon.

The nature of my invention consists in attaching the wires in such a manner, that they can expand and contract with freedom, and so that they shall always have the same 15 tension, or tightness; and of so arranging them on friction rollers that an angle can be made in the fence without increasing the friction on the wires, and so that each and every wire shall have the same degree of 20 tension.

The constructing, making, and erecting of this fence, will be understood, from the following description, reference being had to the accompanying drawings, making a part 25 of this specification.

Figure 1 is an elevation, Fig. 3 is a plan of the fence, and Fig. 2 is an elevation of an intermediate post.

To the post A I secure the shaft B, so 30 that it can revolve freely in the lugs D, and to it I attach the straps c c, &c., so as to wind around it as shown. The wires being fastened to these straps, follows them in their convolutions around the shaft. To 35 the top end of the shaft B I attach the lever or sector F, and to it I fasten the cord J as shown at R; which leads over the sheave G; the sheave being secured in an iron or wooden block on top of the post I. The 40 weight H is secured to the cord, as shown. The wires S S, &c., are strung through the post K, K and lead over the friction rollers o o o, &c., and are fastened to the adjusting screws, in the post P, of which there is only 45 a plan shown. The friction rollers o o o, &c., are secured in blocks, on the outside of the post L. Each wire has its own adjusting screw in the post P, so that they can all be tightened alike. In fencing over hilly or 50 uneven ground, where one post has to be elevated above the other so as to make an angle in the wires, the friction on them becomes so great that it is impossible to draw the wires sufficiently tight, without putting 55 so great a stress on them, as to injure their

strength. I overcome this objection, by placing friction rollers in the post K K as shown at N, by the dotted lines, and lead the wires under them in one post, and over them in the other, and by the use of the friction 60 rollers o o o, &c., (to be used on every post where there is an angle,) I make as many angles in the fence as I please, or as many as may be necessary, and am still able to tighten the wires without obstruction from 65 friction.

After I have the fence erected as above described, I string the wires, and adjust them, by means of the adjusting screws in the post P, until they are all of about the 70 same tension. Then with the lever, or sector, F on the shaft B, I draw up the wires until they are sufficiently tight, I then attach the weight H and cast off the pawl Q. The weight then keeps the wires tight, and 75 rises and falls as they expand or contract. The pawl Q and the ratchet wheel E, are to hold the shaft in position when the wires are being tightened, and are cast off so soon as the weight is applied. The stays, M M, &c., 80 are strung on the wires, so as to fit them, and so that any force coming against one, will be conveyed to, and resisted by all of them, and thus cause the weight H to rise and the wires to yield, to any heavy strain 85 against them.

In fencing over a level plane, I do not design using the friction rollers, shown in the posts K K, but simply a thimble, or thimbles, as shown at T, Fig. 2. There are 90 to be as many of the posts A used, having the shaft, or reel, attached to it, as circumstances may require, and the whole fence to be so modified in construction as to suit the various positions into which it is to be 95 placed.

I do not claim broadly the tightening of the wires by means of a weight; but—

What I claim as my invention and desire to secure by Letters Patent is—

The combination of the shaft P with the post A, and the application of all the wires to the said shaft—whereby all the wires are tightened at one and the same time—by one and the same weight—substantially in 105 the manner set forth.

OLLY WILLIAMS.
